UNITED STATES PATENT OFFICE.

HARRY L. FEASEL, OF NEW YORK, N. Y., ASSIGNOR TO O-SO-EZY MOP COMPANY, A CORPORATION OF MICHIGAN.

MOP AND WRINGER.

1,271,301.

Specification of Letters Patent.

Patented July 2, 1918.

Application filed July 13, 1915. Serial No. 39,655.

To all whom it may concern:

Be it known that I, HARRY L. FEASEL, a citizen of the United States, residing at New York, in the county of New York and State 5 of New York, have invented new and useful Improvements in Mops and Wringers, of which the following is a specification.

This invention relates to a mop-holder having means to expel superfluous moisture 10 from a mop, or similar device, after the same has been saturated with water or other fluid, for scrubbing, rinsing or any other purpose.

One of the objects of the invention is to 15 provide a mop and wringer of simple construction, which may be employed in connection with the mop holder, for expelling moisture from the mop without twisting the latter, or bringing severe strains upon the 20 structure. A further object is to provide a mop wringer which is always ready for immediate use, and which requires no skill to operate. A further object is to provide a carrier constructed for attachment to the 25 usual mop handle, and provided with mop engaging, and mop squeezing members.

The invention will be hereinafter fully set forth and particularly pointed out in the claims.

80 In the accompanying drawing:—

Figure 1 is a perspective view illustrating the invention with the parts in position for using the mop in the usual manner. Fig. 2 is a similar view illustrating the parts in 85 position for applying squeezing pressure to the mop. Fig. 3 is a longitudinal sectional view illustrating the position of the parts at the end of the wringing operation. Fig. 4 is a detail of a slightly modified form of 40 latch.

Referring to the drawing, 10 designates a carrier provided with parallel carrier arms 11, and a socket 12 to which the usual mop handle 13 may be attached in any preferred 45 manner. Rotatably mounted in the free ends of the arms 11, is a mop engaging member 14, provided with oppositely disposed fingers 15, which are spaced from the body of the member 14 to provide a slot 16. 50 The mop 17 is preferably of the endless type, one edge being passed into the slot 16 behind one finger 15, after which the other edge is similarly placed in the slot 16 behind the other finger 15. In this manner 55 the mop is retained in position by said fin-

gers. The mop engaging member 14 is provided with reduced trunnions 18 extending through suitable openings in the arms 11, and one of said trunnions is threaded to receive a nut 19, the other trunnion being provided with an extension 20, angular in cross section, and to which is attached a crank handle 21, by means of which the member 14 may be rotated.

The arms 11 are provided with longitudinal slots 22, in which are slidably mounted the ends of a shaft 23, passed through a squeezing roll 24, whereby said roll is rotatably supported by said shaft. Pivotally attached to said shaft 23, are the arms 25 of 65 a wringer frame 26, corresponding in shape with the carrier 10, the arms 25 being located between the arms 11, and provided at one edge with spaced apart notches 27 arranged to engage the trunnions 18. Pivotally attached to the shaft 23, and slidably therewith is a latch member 28 having a notch 29, arranged to engage the angular portion 20 of the mop engaging member 14, to prevent rotation of said member when 80 the mop is in use.

The carrier 26 is locked in its position within the carrier 10, when the mop is in use, by a spring plunger 30 located within the socket 12, although it is obvious that 85 other forms of locking devices may be employed, such as the spring detent 31 illustrated in Fig. 4. Movement of the wringer frame upon its pivot, in one direction is limited by a stop lug 32 attached to the car- 90 rier 10.

In practice, when the mop is in use the parts are in the position illustrated in Fig. 1, the wringer frame 26 being engaged by the spring plunger 30, and the latch member 95 28 held in engagement with the extension 20 so as to prevent rotation of the mop engaging member. While the parts are in this position the mop may be used in any of the well known ways. When it is desired to 100 expel superfluous moisture, for instance after the mop has been dipped into water for rinsing, the wringer frame is disengaged from the plunger 30, and swung over on the shaft 23 until one of the notches 27 is en- 105 gaged with the mop engaging member 14, thereby releasing the member 14 to rotation, the notch 27 selected for engagement with said member, depending upon the size of the mop. This movement of the wringer 110

frame brings the roll 24 in juxtaposition with the member 14, and relative movement of the roll and member 14 is prevented by reason of the engagement of the notches 27 with said member 14. The operator then grasps the handle 21 and rotates the member 14, winding the mop upon said member, and as the mop is being so wound it passes between the member 14 and wringer roll 24, the space between them being such that as the mop is wound up it is wedged between the roll 24 and the member 14, and all superfluous moisture is squeezed out by the heavy pressure applied thereto. It will be readily seen that no severe strains are brought upon the parts of the device, and that the wringing operation is very simple. After the mop has been completely wound up and the moisture expelled therefrom, the wringer frame is detached from the member 14 and swung back to its normal position, thereby releasing the mop and allowing it to unwind by its own weight. By holding the carrier 10 with the arms 11 slightly depressed, the wringer frame will slide upon the shaft 23 along the slot 22, and bring the latch 28 into engagement with the extension 20, thereby locking the member 14. As the wringer frame drops upon the lug 32 the plunger 30 will engage and lock the same, whereupon the mop is ready for such use as may be desired.

Having thus explained the nature of my invention and described an operative manner of constructing and using the same, although without attempting to set forth all of the forms in which it may be made, or all of the forms of its use, what I claim is:—

- 40 1. An improved mop and wringer comprising a carrier, a mop-engaging member rotatively supported therein, a wringer-frame movably attached to said carrier, a squeezing member carried by said carrier and coöperating with said mop-engaging member and means on said wringer-frame for engaging said mop-engaging member to maintain said squeezing member in fixed relation to said mop-engaging member.
- 45 2. An improved mop and wringer comprising a carrier provided with spaced apart arms, a mop-engaging member rotatively supported by said arms, a wringer-frame attached to said arms and mounted to have pivotal and sliding movement, a squeezing member carried by said wringer-frame coöperating with said mop-engaging member and means to secure said squeezing member at various fixed distances from said mop-engaging member.
- 50 3. An improved mop and wringer comprising a carrier, a mop engaging member rotatably supported thereby, a wringer frame movably attached to said carrier and provided with a squeezing member coöper-

ating with said mop engaging member and locking means for said mop engaging member movable with said wringer frame.

4. An improved mop and wringer comprising a carrier provided with spaced-apart slotted arms, a rotatable member supported by said arms and provided with means for engaging and supporting a mop, a squeezing member mounted in the slots of said carrier and coöperating with said mop-engaging member and means for holding said squeezing and mop-holding members at various fixed distances.

5. An improved mop and wringer comprising a carrier, a mop engaging member rotatably supported thereby and provided with reduced portions, and a wringer frame movably attached to said carrier and provided with a squeezing member to coöperate with said mop engaging member, said wringer frame having notches to engage the reduced portions of said mop engaging member.

6. An improved mop and wringer comprising a carrier provided with spaced apart arms, a mop engaging member rotatably supported by said arms and having reduced portions, and a wringer frame movably attached to said arms and provided with a squeezing member to coöperate with said mop engaging member, said wringer frame being notched to engage the reduced portions of said mop engaging member.

7. An improved mop and wringer comprising a carrier, a mop engaging member rotatably supported thereby, a pivoted wringer frame slidably attached to said carrier and provided with a squeezing member to coöperate with said mop engaging member, and means for locking the wringer frame against pivotal movement and said squeezing member from movement relative to said mop-engaging member.

8. An improved mop and wringer comprising a carrier provided with spaced apart slotted arms, a mop engaging member rotatably supported by said arms, a wringer frame provided with a squeezing member to coöperate with said mop engaging member, a slidable support for said wringer frame mounted in the slots of the arms of said carrier, and a locking device for said mop engaging member, attached to and movable with said slidable support.

9. An improved mop and wringer comprising a carrier provided with spaced apart slotted arms, a mop engaging member rotatably supported by said arms and provided with reduced portions, a wringer frame provided with a squeezing member to coöperate with said mop engaging member, and having notches to engage said reduced portions and a slidable support for the wringer frame mounted in the slots of the arms of said carrier.

10. An improved mop and wringer comprising a carrier provided with spaced apart arms having longitudinal slots therein, a mop engaging member rotatably supported by said arms, a wringer frame provided with means for engaging said mop engaging member, a shaft slidably mounted in said slots and to which said wringer frame is pivotally attached, a squeezing roll 10 mounted on said shaft, and a latch member for said mop engaging member, attached to said shaft.

11. An improved mop and wringer comprising a carrier, a mop engaging member rotatably supported thereby, a wringer frame pivotally supported by said carrier and provided with means for engaging said

mop engaging member, and a squeezing member attached to said wringer frame to coöperate with said mop engaging member. 20

12. An improved mop and wringer, comprising a carrier provided with spaced-apart slotted arms, a rotatable member supported by said arms and provided with means for engaging and supporting a mop, 25 a squeezing member mounted in the slots of said carrier and coöperating with said mop-engaging member and adapted to be held at various fixed distances with respect to said mop-holding member.

In testimony whereof I have hereunto set my hand.

HARRY L. FEASEL.
